UNITED STATES PATENT OFFICE

BURWELL BOYKIN, JR., OF BEAUMONT, TEXAS

SUPPORT

Application filed May 6, 1927. Serial No. 189,275.

My invention relates to jack posts to be employed in connection with drilling rigs and particularly for the support of the draw works including the usual hoisting apparatus.

In the drilling of wells and also in their pumping operations, a hoisting apparatus is an essential element, and it is common to mount at the side of the derrick platform, a frame work supported upon a plurality of jack posts, fitting against the derrick platform and inclined upwardly in a relation parallel with the legs of the derrick. These jack posts furnish with the derrick itself a frame work upon which the draw works may be mounted. Present constructions include wooden posts for this purpose.

It is an object of my invention to provide a steel jack post of improved construction to substitute for the old type of wooden jack post. The invention resides in the adapting of a steel jack post for use in this connection, an object being to form upper and lower attaching brackets by means of which a steel beam may be employed.

Referring to the drawing herewith, Fig. 1 is a side elevation of my jack post shown in the position in which it is mounted upon a well derrick, parts of the derrick being shown in section and broken away. Fig. 2 is a side view of the jack post taken at right angles to the view shown in Fig. 1 and having various parts broken away for greater clearness. Fig. 3 is a transverse section on the plane 3—3 of Fig. 1.

The ordinary derrick with which my invention is to be used customarily has a plurality of supporting members resting upon the ground and I have shown a beam 1 supporting at its ends a sill 2 upon which the platform 3 and other supporting members may be mounted. Above the side sills 2 and spaced therefrom a suitable distance are two spaced beams 4 which are ordinarily called the head boards. These two boards extend across the side of the derrick parallel with the platform and are connected at their ends to the supporting legs of the derrick. They are, therefore, inclined slightly from the ver-

tical to correspond with the inclination of the legs of the derrick.

My jack post is adapted to be mounted in position upon the derrick, thus constructed. It comprises a steel beam A, of what is termed H-beam construction, having two side plates 5 connected by a central web 5.

At the lower end of the beam A, I provide an attaching bracket B. Said bracket has two upper plates 6 which, as shown in Fig. 2, are spaced apart a suitable distance to receive between them the web 5 of the beam. Transverse openings through the plates 6 and the web 5 are provided to receive bolts 7 by means of which the bracket may be secured to the post. Below the two upper plates 6 is a plate 8, which is set at a slight angle to the plate 6 and has on its lower side a squared recess 9 to fit about the sill 2 of the derrick. The lower extension 10 upon the plate which fits against the outer side of the sill 2 may be recessed for lightness of construction and has a central opening 11 therethrough to receive a bolt 12 by means of which the post is firmly secured to the sill of the derrick.

The upper end of the beam is formed with a bracket C, which is shaped to fit between the two head boards 4. The bracket has attaching plates 13 fitting on opposite sides of the web 5 of the beam and secured thereto by bolts 7'. The plate has an upwardly extending arm 14 which is preferably made hollow and has a central recess 15 therein for purposes of lightening the weight thereof. This arm 14 is adapted to fit between the two head boards 4 and has a transverse opening 16 therethrough to receive a clamping bolt 17, by means of which it is secured firmly to the head boards for support.

This post is of extremely simple construction, but when thus formed with the attaching plates at each end thereof secured to the web by means of the bolts 7 and 7', the said plates fit against the ends of the beam and are rigidly attached thereto in such manner that the beam is rigid and strong. The brackets are so shaped as to fit against the parts of the derrick which are ordinarily employed, and it will be possible, therefore, to secure the jack post shown, in position for supporting

the draw works with a minimum of time and effort.

Having thus described my invention, what I claim as new and desire to protect by Letters Patent is:

A jack post including a steel body of H-beam construction adapted to stand at an angle from the vertical, a lower metal bracket including a plate to engage the upper side 10 of a derrick sill, two upwardly extending arms transversely of said plate and adapted to straddle the central web of said H-beam, means to secure said arms to said web, a pair of downwardly extending connected plates 15 on said bracket to engage the side of the derrick sill, a reinforcing web between said plates, and a bolt to connect said bracket to said sill.

In testimony whereof I hereunto affix my 20 signature this 23rd day of April A. D. 1927.
